UNITED STATES PATENT OFFICE.

JOSEPH JACQUES JULES SAUVEUR, OF MONTREAL, QUEBEC, CANADA.

SHOCK-ABSORBER.

1,177,654.

Specification of Letters Patent.

Patented Apr. 4, 1916.

Application filed October 23, 1914. Serial No. 868,284.

To all whom it may concern:

Be it known that I, JOSEPH JACQUES JULES SAUVEUR, a subject of the King of Great Britain, and residing at the city of 5 Montreal, in the Province of Quebec, in the Dominion of Canada, have invented certain new and useful Improvements in Shock-Abso-
10 rbers; and I do hereby declare that the following is a full, clear, and exact de-
scription of the same.

The invention relates to a "shock absorber" and the object is to provide a device of this character, simple to construct and having certain adjustable features 15 which greatly increase the efficiency of the device and secure its applicability to varying conditions of load.

The invention will be better understood with the aid of the accompanying drawings 20 in which—

Figure 1 is an elevation showing the invention applied to a vehicle spring. Fig. 2 is a perspective view of the device separated from the vehicle spring. Fig. 3 is a 25 vertical sectional view. Fig. 4 is an under side plan view.

The device is built up of a number of component parts of which the opposite side rods 1 are distanced and coupled by plates 30 2 and 3, upper and lower respectively, the former being rigidly secured on the rods 1 and in any suitable manner and carrying 35 a stuffing box 4. Between the upper and lower plates, a cylinder 5 is secured cen-
trally between the rods 1, this cylinder be-
ing a simple open ended tube and engaging 40 the plates 2 and 3 by fitting in suitable recesses 6 therein. This cylinder 5 is held very tightly between the two plates by the clamping nuts 7 threaded on to the threaded lower end of the rods 1.

The upper ends of the rods 1 form journals for a pivot pin 8 which is passed therethrough and through the looped outer end 45 of the vehicle spring 9.

10 is a cup shaped piston loosely fitting the cylinder 5 and having a piston rod 11 extending upwardly through the stuffing box 4 and provided at its upper end with 50 an internal thread 12 engaged by the shank 13 of a fork 14 through which a pivot pin 15 is passed into engagement with the curled outer end of the vehicle frame 16; thus it will be seen that the piston 10 moves up and 55 down within the cylinder 5 as the body of

the vehicle moves over a rough surfaced road.

17 is a plate loosely disposed within the bottom of the cylinder 5 between which and the upper end of the piston 10 a spring 18 is disposed. A second and shorter spring 19 assisting the main spring to take up any extraordinary shock may be disposed within the spring 18.

As thus far described, the invention would 65 be hardly suitable for varying loads and I therefore provide an adjustment of the springs in such a manner that they may be readily regulated to suit a light or heavy load. This adjustment is accomplished 70 through the medium of set pins 20 threaded through the bottom plate 3 and abutting the plate 17. The set pins 20 are preferably four in number at distanced points as it is necessary that the plate 17 shall be not al-
lowed to tip. It will be seen that if there 75 are any breakages, it is a very easy matter with this particular construction to quickly take apart or separate the device and put in a new part to replace the broken part. 80

Of course, I am aware that it is not new to apply a shock absorber between the parts 9 and 16 as illustrated in Fig. 1, but this view is provided to assist the better understand-
ing of the invention, the operation of 85 which will readily be understood from the foregoing description of the parts.

In the stuffing box 4, in place of the ordinary packing, is provided a metal bushing 21 which, being oiled from a suitable oil 90 cup, facilitates the sliding of the piston 11 and when worn can be easily replaced by simply removing the stuffing box nut and unscrewing the piston rod from the fork 14.

What I claim is:—

A shock absorber comprising, a pair of connecting rods, means of connecting the same to a vehicle body, a top plate fixed to said rod and provided with an opening, a bottom plate inwardly mounted on said rods, 100 a cylinder adapted to be clamped between said plates, nuts threaded upon the lower ends of said rods and adapted to force the lower plate into clamping position, a cushioning spring within said cylinder, a cup 105 piston slideable within said cylinder and partially inclosing said spring, a rod extending from said piston through the opening in the top plate, a connecting fork carried thereby, a pressure plate resting in the bottom of 110

said cylinder and seating the aforesaid spring, and a plurality of set screws equally spaced about the center of the aforesaid bottom plate and threaded therethrough 5 into engagement with said pressure plate to regulate the tension of the spring and prevent tilting of the plate.

Signed at Montreal, Quebec, Canada, this 2nd day of July, 1914.

JOSEPH JACQUES JULES SAUVEUR.
